UNITED STATES PATENT OFFICE.

OTTO A. LEHMAN, OF HOBOKEN, NEW JERSEY.

DESIGN FOR AN APPAREL-BELT.

SPECIFICATION forming part of Design No. 35,823, dated March 18, 1902.

Application filed February 20, 1902. Serial No. 94,995. Term of patent 3½ years.

To all whom it may concern:

Be it known that I, OTTO A. LEHMAN, a citizen of the United States, and a resident of Hoboken, in the county of Hudson and State of New Jersey, have invented a new and useful original Design for an Apparel-Belt, of which the following is a specification, reference being had to the accompanying drawing, forming part thereof, in which the figure represents a face view of the apparel-belt embodying my design.

As shown in the drawing, the leading or material feature of my design consists in an apparel-belt having a general curved form from end to end, the lower edge thereof presenting a continuous convex line 1 and the upper edge presenting two concave lines 2 and 3, meeting at the middle portion of the belt in a rounded point 4, the face of the belt being

ornamented by two figures formed by ribs 20 raised from the surface of the belt, each figure comprising upper and lower ribs 5 and 6, following the contour of the belt for a distance along the same, their outer ends being joined together and their inner ends being 25 joined together by two short inwardly-extended ribs 7 and 8.

What I claim is—

The design for an apparel-belt, substantially as herein shown and described. 30

In testimony that I claim the foregoing as my invention I have signed my name, in presence of two witnesses, this 13th day of February, A. D. 1902.

OTTO A. LEHMAN.
